UNITED STATES PATENT OFFICE

LEWIS G. DAVIS, OF ROCKFORD, ILLINOIS

MOLDING MACHINE

Application filed November 1, 1929. Serial No. 404,116.

My invention relates to molding machines and has special reference to means for preventing the sand commonly employed in this type of machine from coming in contact with 5 hydraulic pistons whereby the piston becomes excessively worn and its value materially impaired.

A common type of molding machine is one having a pattern bed arranged to lie on one side of the machine upon which a pattern is fixed. The flask is normally positioned upon the pattern bed about the pattern and the space between the flask and pattern filled with sand. The excess of sand is scraped 15 from the flask and much of it falls upon the pattern bed around the sides of the flask. A board is placed upon the top of the flask and fastened in this position after which the pattern bed, flask, and board are rotated 20 through a half circle depositing the flask with the board on its lower side upon a draw or receiving table. The pattern and pattern bed are then vibrated by automatic means whereby the pattern is loosened from the 25 mold of sand. The pattern bed and pattern are then rotated back to their first position leaving the flask and mold upon the draw table.

When the flask is placed upon the draw 30 table the sand which was upon the receiving table, on the outside of the flask, is deposited on the floor or frame of the machine at the sides of the draw table. The draw table is provided on its under side with a hydraulic 35 piston whereby it may be raised or lowered at each molding operation. The sand thus deposited tends to pile up around the sides of the table, and soon reaches a point where it begins to run in and come in contact with 40 the exposed portion of the piston. In order to obviate this difficulty it has been customary in the past to provide a canvas or cloth which has been draped about the piston from a point beneath the table. This, 45 however, has not been entirely satisfactory because of the fact that guide rods and other moving parts near the piston have a tendency to catch the canvas and tear it, unknown to the operator, whereby sand is again carried 50 into the piston. The disastrous effects of

sand reaching this piston are obvious. The piston, because of its hydraulic operation, is covered with a coating of oil. The sand clings to this oil and when the piston returns into the cylinder the sand is carried in between the cylinders and piston walls, causing very rapid wearing of the parts. In addition to this rapid wear the sand causes the piston and other parts to stick in their downward movement giving the table an erratic, jerky 55 movement. This jerky movement causes the delicate mold upon the table to disintegrate thus dissipating the work of the operator.

One of the principal objects of my invention is the provision of improved means for preventing the access of sand to the piston and the moving parts near the piston. I have aimed to provide a more positive operating means than the canvas of the prior art, 60 whereby no special care is required in the removal of the sand and in the operation of the machine to prevent the accumulation of sand.

Another object is the provision of a sand 65 guard of this character having considerably longer life than the guards of the prior art which consists in a telescoping wall arranged to completely enclose the piston and extend from the draw table to the frame beneath the table.

Other objects and attendant advantages 70 will become apparent to those skilled in the art from the following description and the accompanying drawings in which—

Figure 1 is a vertical section through the 75 sand guard as applied to a conventional draw table and piston;

Fig. 2 is an enlarged section through one side of the guard showing the manner in which the sections are connected together;

Fig. 3 is a fragmentary view of the interior 80 of the guard showing connecting members; and

Fig. 4 is a vertical section through one side 85 of the guard showing it in its extended position.

The guard as shown consists generally of three telescoping sections indicated by the numerals 5, 6, and 7 and a plurality of connecting members presently to be described. 90

While I have shown the guard as consisting of three members it will be apparent that any suitable number of these members may be employed. In this instance the guard is shown as being rectangular in form but here again it will be apparent that any suitable shape may be given the members. The upper member 5 is adapted to be attached to the sides 8 of a draw table 9 by means of screws or bolts 10. The member 5 extends on all four sides of the rectangular table 9 and projects downward therefrom. In order that the section may move through accumulated sand with a minimum resistance the lower edge thereof is beveled as shown at 11. Section 5 is made to closely fit against the outer wall of section 6 which is positioned therewithin. Section 6 is also provided with a beveled lower edge 12 similar to the edge 11 of section 5, and is supported upon section 5 by means of bolts 13 which are securely fastened to the latter through brackets 14 and nuts 15 and 16, threaded upon bolts 13 near their ends. Brackets 17 attached to section 6 are provided with an opening through which bolts 13 are permitted to slide. Heads 18 on the bolts 13 limit this sliding movement of the bolts 13 in the brackets 17. The brackets 17 are also provided with an opening 30 through which bolts 19 are securely fastened to the brackets through nuts 20 and 21, the bolts 19 have slid engagement with an opening in brackets 22 positioned upon the upper edge of the section 7. A head 23 on the lower end of the bolts 19 limits the upward movement of the bolts 19 in the brackets 22. Any number of these connecting bolts may be employed but I have found it convenient to employ at least one set on each side of the guard. Section 7 is positioned on the inner side of section 6 and is of such size as to cause the inner walls of the sections 6 and 7 to fit closely against each other. The section 7 is fixedly attached to the frame 24 of the molding machine through bolts or screws 25 passing through a flange 26 on the lower end of the section 7.

In the operation of the device section 5 is adapted to move closely over the outer surface of section 6 and section 6 to move closely over the outer surface of section 7, the amount of this movement being regulated by the length of the rods 13 and 19. If oil or other fluid is admitted to the interior of the cylinder 27 the piston 28 supporting the draw table 9 is caused to move upward a distance regulated by a stop attached to the piston. This stop consists of a regulating collar 29 attachable to the piston 28 at any desired elevation. A rod 30 moving through a flange 31 is positioned in the collar 29 through a nut 32 whereby the length of this rod determines the distance through which the table 9 may move. Guide rods 33 are attached to the bottom of the table 9 and serve to guide

the collar 29. These guide rods are adapted to move downward through suitable openings in the frame 24 as the table 9 moves toward its lower position.

The table is shown in Fig. 1 in a partly elevated position the lower ends of the guide rods 33 having emerged from the openings in the frame 24. During the movement upward to this position the section 5 has moved upward from the position shown in Fig. 2 to the position shown in Fig. 1, the rod 13 moving through the brackets 17 to permit this. However, at this position the head 18 of the rod 13 has reached the bracket 17 stopping further relative movement between section 5 and section 6. As the table continues to move upward from the position shown in Fig. 1 the head 18 will bear against the bracket 17 causing the section 6 to be moved over the surface of section 7, the sections eventually reaching the position shown in Fig. 4.

This movement of the sections will be reversed when the table is caused to move downward, in which instance the sections will move over each other from the position shown in Fig. 4 to the position shown in Fig. 2. It will be seen that the beveled edges 11 and 12 of the two upper sections 5 and 6 will cause any sand which may lie against the surface of section 7 to be moved outward, away from the surface permitting the two sections to move downward. Sufficient power will be provided by the weight of the table 9 and attached parts to force these two sections down against the resistance of the sand.

Obviously, by this arrangement no sand is permitted to enter within the enclosure formed by the guard and consequently the sand will not be permitted to pile up against the piston 28 or the rod 30. These parts will at all times be permitted to slide smoothly through their bearings unhampered by the presence of small particles of sand; without the constant attention of the operator. It will also be immaterial to what height the sand may rest against the outer walls of the guard since there is no point between the frame 24 and the table 9 at which sand may enter thereunder. The construction of the guard is such as to be highly durable and economical to manufacture.

While I have thus described and illustrated a specific embodiment of my invention I am aware that numerous alterations and changes may be made therein without departing from the spirit of my invention and I do not wish to be limited except as required by the prior art and the scope of the appended claims in which—

I claim:

1. In a molding machine having a frame, a draw table, and a hydraulic piston therebetween for raising and lowering said table, a sectional wall positioned between said table

- and said frame adapted to enclose said piston to prevent the entrance of sand comprising, a plurality of overlapping sections, the outer section being movable with said piston and the inner section being attached to the frame, a plurality of rods parallelly positioned with respect to said wall arranged to connect said sections, each of said rods being fixedly attached near the top of one of said sections 5 and slidably attached to the next succeeding section whereby raising of said table will cause slidable movement of the first section over said succeeding section for a predetermined distance and concordant movement of 10 said sections thereafter, said movement causing said sectional wall to unfold with the raising of said table whereby the sand resting against said wall is prevented from reaching said piston.
- 20 2. In a molding machine having a frame, a draw table, and a hydraulic piston therebetween arranged to move into and out of said frame for raising and lowering said table, a telescoping wall connecting said frame and 25 said table adapted to enclose the exposed portion of said piston comprising, a suspended wall section attached at its upper edge to said table and having its lower edge tapered toward its inner edge, a lower wall section attached at its lower edge to said frame, at 30 least one intermediate section having its lower edge tapered toward the inner side, said lower and intermediate sections being arranged to closely fit within said suspended 35 section in telescoping relation, and means for maintaining said sections in telescoping relation including a plurality of rods positioned on the inner side of said wall and substantially parallel thereto, connecting said sections 40 in sliding engagement whereby successive sections are caused to be raised as said table is raised.
3. In a molding machine having a frame, a draw table, and a hydraulic piston there- 45 between for raising and lowering the latter, a sand guard adapted to enclose the exposed portion of said piston comprising a lower member fixedly attached to said frame beneath said table, an upper member fixedly 50 connected with said table and arranged to slide over said lower member, at least one intermediate member positioned between said lower and said upper member, said upper and said intermediate member being adapted to 55 slide over said lower member in telescoping engagement as said table moves up and down, and means for preventing said members from becoming separated from said engagement when the table moves up, said members act- 60 ing to prevent the admission of sand to the moving parts enclosed therein.
4. In a molding machine having a frame, a draw table, and a hydraulic piston therebetween for raising and lowering the former, a 65 telescoping sand guard adapted to enclose the exposed portion of said piston comprising a plurality of overlapping members, the inner member thereof being attached to said frame and the outer member being attached to said table, means attached to said outer member adapted to raise successive members as said table is raised whereby a continuous wall is provided at different elevations of the table, to prevent loose sand resting against said guard from reaching said piston.
5. In a molding machine having a draw table and a hydraulic piston therebeneath for raising and lowering the former, a telescoping sand guard adapted to enclose the exposed portion of said piston comprising an upper member fixedly connected to and movable with said piston, a lower member fixedly below said table, at least one intermediate member arranged to be raised or lowered by 80 said upper member, and means slidably connecting said members.
6. In a molding machine having a draw table adapted to receive a mold, a frame, and a hydraulic piston therebetween for raising and lowering said table, a sectional wall arranged to prevent sand falling from said table from contacting with said piston, comprising a vertical upper wall section attached at its upper end to move with said table and having its lower edge inwardly beveled, at 90 least one intermediate section positioned within said upper section having its lower edge inwardly beveled, a lower section positioned within said intermediate section and 95 attached to said frame, said upper and intermediate sections being arranged to move vertically in accord with said table with respect to said lower section and with respect to each other to provide a continuous wall enclosing 100 said piston at all positions of said table, and means connecting said sections to permit such movement.
- In witness of the foregoing I affix my signature.
